REGISTERING DEVICE

Filed Oct. 17, 1924

UNITED STATES PATENT OFFICE

KARL ANSTOTZ, OF NEW YORK, N. Y., ASSIGNOR TO OHMER FARE REGISTER COMPANY,
OF DAYTON, OHIO, A CORPORATION OF NEW YORK

REGISTERING DEVICE

Application filed October 17, 1924. Serial No. 744,128.

This invention relates to a detent for holding a toothed wheel against reverse movement and is designed more particularly for use in a registering device of the type known as a hubodometer. The ordinary hubodometer comprises a registering device mounted within the hub cap of a wheel, the travel of which is to be measured. The actuating device for the registering mechanism is of such a character that the rotation of the hub relative to the fixed axle on which the wheel is mounted will cause the operation of the registering device. In order that such a registering device may be applied to wheels of different diameters the driving mechanism usually includes a pawl and ratchet mechanism, the ratchet wheel of which is removable so that ratchet wheels of different sizes may be inserted in the mechanism to accommodate the same to wheels of different diameters. The actuating pawl for the ratchet wheel may be adjusted or changed to accommodate it to different ratchet wheels as may be desired. It has been customary to mount the detent pawl, which prevents the reverse movement of the ratchet wheel, on a fixed axis and it has been necessary to reshape or cut away the pawl to accommodate it to ratchet wheels of different sizes. This reshaping of the pawl is a more or less difficult and tedious operation and adds considerable to the expense of constructing and installing the device.

One object of the present invention is to provide a pawl which can be readily accommodated to ratchet wheels of different sizes without reshaping or modifying the pawl itself in any way.

A further object of the invention is to provide an adjustable supporting device upon which the pawl may be mounted and the adjustment of which will so shift the position of the axis of the pawl as to properly accommodate it to ratchet wheels of different sizes.

A further object of the invention is to provide such a device which will be very simple in its construction and which may be very easily adjusted.

Other objects of the invention will appear as the mechanism is described in detail.

In the accompanying drawings Fig. 1 is a longitudinal sectional view of a hubodometer embodying my invention taken on the line 1—1 of Fig. 2; Fig. 2 is a front elevation of the registering mechanism partly broken away; and Fig. 3 is a detail view of the operating device for the actuating pawl.

In these drawings I have illustrated one embodiment of my invention and have shown the same as applied to a hubodometer of a known construction but it will be understood that this particular embodiment has been chosen for the purpose of illustration only, that the invention may take various forms and may be applied to registering devices of various kinds without departing from the spirit thereof.

In that form of the device here shown the hubodometer as a whole is mounted in a hub cap 1 which is secured to the hub of the wheel, the travel of which is to be measured. This wheel is rotatably mounted on a spindle or axle 2 and is secured thereon by a nut 3. In this particular device the registering mechanism does not rotate with the wheel but remains stationary so that it is always in a position in which a reading may readily be taken therefrom. The outer end of the hub cap is provided with an opening 4, preferably closed by a glass 5, through which the reading may be taken. The registering mechanism itself comprises a series of indicators or dials 6, of which there may be any suitable number. These dials are mounted on studs or pins 7 which in turn are mounted upon a supporting structure here shown in the form of a plate 8 which is so mounted in the hub cap that it will be held against rotation and the hub cap permitted to rotate about the same. To this end the plate 8 is here shown as having an inwardly extending shank or stud 9 journaled in a bearing 10 formed central of a plate or supporting member 11 which is rigidly secured to the hub cap so that it will revolve about the stud 9. In the present instance the plate 11 is provided with a screw threaded flange 12 which is threaded into a boss 13 forming part of the hub cap and extending about the

opening or recess 14 in which the registering device is mounted. The stud 9 of the supporting plate 8 may be secured in the bearing 10 in any suitable manner but, as here shown, a bearing plate 15 is rigidly secured to that end of the stud which projects beyond the inner end of the bearing 10 and antifriction balls 16 are inserted between this bearing plate and the front wall of an annular recess 17 formed in the rotatable plate 11. The stud 9 is so connected with the spindle 2 that the supporting plate 8 and registering mechanism will be held against rotation. As here shown a bracket 18 is rigidly secured to the bearing plate 15 and is provided with rearwardly extending arms 19 provided with longitudinal slots 20 to receive fingers 21 carried by a movable plate or spider 22. This spider has rearwardly extending lugs 23 arranged to enter recesses 24 in the nut 3, which is mounted on the spindle 2. The spider 22 is yieldable toward and from the nut to permit the mechanism to be readily mounted on the hub of the wheel and a spring 25 confined between the spider 22 and the bearing plate 15 presses the spider toward the spindle and holds the lugs 23 in the recesses in the nut.

The driving mechanism for the registering device, consisting of the dials 6, may be of any suitable character but preferably consists of a train of gearing 26 with which is connected a ratchet wheel 27. Cooperating with the ratchet wheel is an actuating pawl 28 to which movement is imparted to rotate the ratchet wheel, this movement being transmitted through the gear train to the dials. In the present device the pawl is carried by a pin 29 which is slidably mounted in a slot 30 formed in the supporting plate 8 and so arranged that the transverse movement of the pin in the slot 30 will impart the desired movement to the pawl. The pin 29 is mounted in an arm 31 forming part of a yoke or eccentric strap 32, which is mounted on an eccentric boss or bearing 33 secured to the rotatable plate 11 and preferably formed integral with the bearing 10. The pin 29 being mounted in the slot in the plate 8 it would be apparent that the yoke or eccentric strap will be held against rotation and that reciprocatory movement will be imparted thereto by the rotation of the eccentric boss within the same, thus causing the pawl to be actuated.

The mechanism so far described can be applied to the hubs of wheels of various diameters without changing any part thereof, other than the ratchet wheel 27. Consequently the device can be manufactured complete without regard to the diameter of the wheel to which it is to be applied and when the device is to be installed it is provided with a ratchet wheel 27 of a size to properly operate the registering mechanism according to the diameter of the wheel. It is, of

course, necessary that the ratchet wheel should be held against reverse movement and to this end a detent pawl 34 is provided and in order that this pawl may be accommodated to ratchet wheels of different sizes and may so engage the teeth of any such ratchet wheel as to prevent all reverse movement or back lash on the part of that ratchet wheel I have mounted the pawl on an adjustable axis and by adjusting the axis of the pawl the latter may be properly positioned with relation to any ratchet wheel which may be inserted in the device. The pawl may be mounted in various ways but, in the device here shown, I have utilized an elongated supporting member or plate 35 which is pivotally mounted on the supporting plate 8 which carries the registering mechanism, in the present instance at the center of said plate. In the present construction this plate is pivotally mounted on a screw threaded stud 36 by means of which the face plate 37 is secured to the supporting plate 8, this face plate having openings 38 through which the numerals on the various dials may be read. The pawl 34 is pivotally mounted on one end of the elongated plate or lever 35 and the other end of this plate is enlarged and provided with an arcuate slot 39 through which extends a screw 40 which is threaded into the plate 8 and which when tightened down serves to hold the elongated plate 35 against all movement about its axis and to provide a fixed support for the pawl 34. It will be obvious that by loosening the screw 40 the plate 35 may be adjusted until the pawl 34 is properly positioned with relation to the ratchet wheel and by then tightening down the screw 40 the pawl is firmly secured in this position. The adjustment of the plate is thus very easily accomplished and the shifting of the axis of the pawl enables the latter to be very accurately positioned with relation to the ratchet wheel, thereby enabling the assembling and installation of the registering device to be quickly and easily accomplished.

While I have shown and described one embodiment of my invention I wish it to be understood that I do not desire to be limited to the details thereof as various modifications may appear to a person skilled in the art.

Having now fully described my invention, what I claim as new and desire to secure by Letters Patent is:

1. In a device of the character described comprising mechanism which includes a toothed wheel, a pawl carrier pivotally mounted on a normally fixed axis, a detent pawl pivotally mounted on said carrier and arranged to engage said toothed wheel, and means for securing said pawl carrier in adjusted positions to operatively position said pawl with relation to toothed wheels of different diameters.

2. In a device of the character described comprising a supporting structure and mechanism mounted on said supporting structure and including a toothed wheel, a pawl carrier 5 adjustably mounted on said supporting structure, and a detent pawl pivotally mounted on said carrier, arranged to engage said toothed wheel and movable with said carrier into different operative positions.
- 10 3. In a device of the character described comprising a supporting structure and mechanism mounted on said supporting structure and including a toothed wheel, an elongated plate pivotally mounted on said supporting 15 structure and having a slot in one end thereof, a pawl pivotally mounted on the other end of said plate and arranged to engage said toothed wheel, and a screw extending through the slot in said plate and threaded into said 20 supporting structure.
4. In a device of the character described, a mechanism comprising a toothed wheel, a detent pawl pivotally mounted on a normally fixed axis adjacent to said toothed wheel and 25 arranged to engage the same, and means for shifting the axis of said detent pawl and for securing the same in its adjusted position.
5. In a device of the character described, a mechanism comprising a toothed wheel, a 30 pawl carrier pivotally mounted adjacent to said toothed wheel and held normally against movement, a detent pawl pivotally mounted on said pawl carrier and arranged to engage said toothed wheel, and means for securing 35 said pawl carrier in adjusted positions about its axis.
6. In a device of the character described comprising mechanism which includes a toothed wheel, a supporting member mounted 40 for adjustment with relation to said toothed wheel, and a detent pawl mounted on said supporting member for operative movement with relation thereto and arranged to engage 45 said toothed wheel in various positions of said supporting member.

In testimony whereof, I affix my signature
hereto.

KARL ANSTOTZ.
